ROOFING TILE

Charles N. Pretty, Vancouver, British Columbia,
Canada

Application January 7, 1947, Serial No. 720,637

3 Claims. (CL 108—10)

1
This invention relates to improvements in tiles. An object of the invention is the provision of an improved tile for use in roofing in which the tiles have interfitting and overlapped elements dovetailing into each other in combination with a plurality of gutters so arranged that water will not only be drained away from the overlapped portions of the tiles but such arrangement will afford an effective barrier against wind and water during storms.

Another object of the invention is the provision of an improved tile for roofing purposes in which each tile has a lateral flange at each side edge, the flanges being at different horizontal levels with the adjacent flanges of a series of tiles neatly fitting into each other, one flange of each tile having a plurality of longitudinal gutters which are covered by the adjacent flanges on a juxtaposed tile, each tile in the longitudinal rows running from the eaves of the roof to the ridge pole thereof being provided with a transverse groove at the under face near the lower end of said tile and a transverse rib on the outer face adjacent the upper end, the rib of one tile being received by the groove of an adjacent tile, the upper end of the second mentioned flange having surface grooves leading at one side edge into a vertical groove which communicates with the gutters in the first mentioned lateral flange, the grooves and gutters cooperating to drain moisture from the tiles while preventing water from being blown upwardly through the gutters.

A further object of the invention is the provision of a tile so constructed that the tiles may be interfitted in a leakproof manner in series of transverse and longitudinal rows on a roof, the interfitting parts including means for checking water from leaking or blowing through the joined portions, the tiles being simply made, light in weight, constructed for convenience in packing and providing desirable characteristics for a dry, durable and easily laid roof.

The invention consists in the novel construction, arrangement and combinations of parts hereinafter more particularly described and claimed.

In the drawings:

Figure 1 is a plan view of a tile constructed in accordance with the principles of my invention.

Figure 2 is a longitudinal side edge in elevation of the tile.

Figure 3 is a longitudinal view of the opposite or other side edge of the tile.

Figure 4 is a longitudinal vertical section taken along the line 4—4 of Figure 1.

2
Figure 5 is a transverse vertical section taken along the line 5—5 of Figure 1.

Figure 6 is an enlarged fragmentary lower end view of two juxtaposed tiles showing the overlapped portions of the tiles in position, and

Figure 7 is an enlarged fragmentary side view of a pair of tiles showing the overlapping portion of the lower end of one tile in position on a preceding tile.

Referring more particularly to the drawings, 10 designates a tile having a lateral flange 11 upon which is placed a lateral flange 12 of a juxtaposed tile 13. These tiles are arranged in transverse rows on a roof. A tile 14 has a transverse groove 15 at the under face adjacent the lower edge and this groove receives a rib 16 on the outer face at the upper end of the tile 10 when succeeding transverse rows of tiles are secured in position on the roof.

The tiles 10, 13 and 14 are identical in construction so that each tile has the lateral flanges 11 and 12 at opposite sides thereof and the rib at the upper end and the groove 15 in the under face at the lower end. In other words, the tile 10 illustrated in Figures 1 to 5 inclusive is so constructed that a series of such tiles may be interfitted in rows across the roof in longitudinal rows as will be appreciated as the description proceeds.

The flange 11 has its upper surface below the plane passing through the upper surface of the tile. One end of the rib 16 is cut away at 20, so that the depressed surface of the flange extends at its upper end beyond the lower edge 21 of said rib. The surface of the flange is provided with longitudinal gutters 22 and a V-shaped groove 23. These gutters and the groove extend downwardly from the cut-away portion 20 of the rib 16 to and through the lower end of the flange.

The flange 12 at the opposite edge of the tile is complementally formed with respect to the flange 11 and fits neatly onto the flange 11 of a juxtaposed tile 24 (Fig. 5), so that tiles placed in transverse rows will present a flat surface. Furthermore, the flanges 12 provide covers for the gutters 22. A depending rib 25, V-shaped in cross section, fits neatly into the groove 23 in the flange 11.

The outer surface on the upper end of the flange 12 is provided with connected gutters 26, 27 and 28, and the lower ends of the gutters 27 and 28 merge into each other and empty into a vertical groove 30 at one side edge of each tile. The groove 30 is positioned so as to be covered by the lower portion of a superposed tile. Said groove drains moisture into the gutters 22 in the

flange 11. Since the tiles are inclined on the roof such moisture will drain downwardly onto the outer surface of the tile which is at a lower level.

It will be noted from Figure 1, that the rib 16 is cut away at 31 along the right side of the tile to form a narrow section 32 of the rib so that said section will neatly fit against the narrow section 33 at the other end of the rib and over the upper ends of the gutters 22 and the groove 23. The fitted sections 32 and 33 have the same width of rib 16.

The under face of each tile has pockets 35 which reduce the weight of the tiles. The outer or upper face of each tile has a groove 36 or gutter adjacent each side edge for draining away surface water to the next lower tile, thus preventing such water from spilling over the side edges of the tiles into the gutters 22.

The upper end of each tile has a pair of spaced projections or lugs 40 which are provided with a keyhole slot 41 to receive a nail which is driven into the roof prior to the application of the tile. The heads of the nails are received by circular openings 42 of the slots and the tile is pulled downwardly so that the nails are received by the narrow portions 43 of the slots with the heads being seated within pockets 44 in the lug.

The under face of each tile at the upper end is sheared away as shown at 45, as are the lugs 40 for not only facilitating the application of the driven nails but to give to the tiles the proper slant when the lower ends of the tile are overlapped on the upper ends of the preceding tiles in the vertical rows of the tiles on the roof.

When the tiles have been applied to a roof with the flanges 11 and 12 in overlapped relation, the cooperating sections 32 and 33 at the ends of the ribs which are in substantial dovetailed relation will cooperate with the gutters or grooves 26, 27 and 28 and groove 30 to form a simplified and effective barrier against wind and water. The gutters 22 drain away any moisture so that during low temperatures no water will remain between the tiles to be frozen.

Although a preferred and practical embodiment of the invention is disclosed herein, it is to be understood that various modifications may be made within the scope of the appended claims.

I claim:

1. A tile adapted to be laid in a series of transverse rows and longitudinal rows on a roof, each tile having a flange along the side edges thereof, the flanges at one edge of the tiles being at a lower level than the flanges at the other side edges so that adjacent flanges on juxtaposed tiles will be overlapped, said tile having a transverse groove at the under surface adjacent the lower end, a rib at the upper end of each tile adapted to be received by the groove in a succeeding tile in a longitudinal row, the flanges at the lower levels having longitudinal gutters

5
10

which are covered by the overlapping flanges on the juxtaposed tiles, each overlapping flange being provided with a vertical groove in the side edge thereof positioned so as to be covered by the lower portion of a superposed tile and gutters in the outer face communicating with the vertical groove and the gutters in the flanges at the lower level of juxtaposed tiles, the ends of the ribs having cut-away portions, the cut-away portion at one end of the rib on one tile being complementary to the cut-away portion on the adjacent end of the rib on a juxtaposed tile so that the adjacent ends of the ribs will interfit.

2. A tile having substantially flat upper and lower surfaces, a rib projecting upwardly along the upper edge of the tile, said tile having a flange at each side edge and having approximately one-half the thickness of the tile, one flange having its upper surface flush with the upper surface of the body of the tile, the other flange having its under surface flush with the bottom surface of the tile, the second-mentioned flange having longitudinal gutters, the lower end of tile at the bottom surface being provided with a transverse groove, and spaced lugs projecting upwardly from the upper edge of the tile and provided each with a bayonet slot to receive a fastening means, the bottom surfaces of the lugs and the upper under surface of the tile being beveled and lying in a common plane.

3. A tile adapted to be laid in a series of transverse rows and longitudinal rows on a roof, each tile having a rib at the upper end on the upper surface and a groove at the lower end in the undersurface, the ribs of the tiles being received by the grooves of the succeeding tiles in the longitudinal rows, a flange at the side edges of each tile, the adjacently disposed flanges in transverse rows being complementary to each other so that the flanges may be fitted into each other in overlapped relation, the underlying one of said flanges being provided with longitudinal gutters, the ends of the ribs being cut-away so that an end of one rib on one tile may be fitted 45 into the adjacent end of a rib of a juxtaposed tile in the transverse rows when the adjacently disposed flanges on the tiles are placed in overlapping positions, said interfitted ends of the tiles being located over the upper ends of the longitudinal grooves to prevent water from being blown upwardly through the longitudinal grooves.
